UNITED STATES PATENT OFFICE

124,708

DESIGN FOR A COMBINATION CALENDAR MEMORANDUM PAD

Charles F. Brown, Greeneville, Tenn.

Application November 6, 1940, Serial No. 96,365

Term of patent 7 years

To all whom it may concern:

Be it known that I, Charles F. Brown, a citizen of the United States, residing at Greeneville, in the county of Greene and State of Tennessee, have invented a new, original, and ornamental Design for a Combination Calendar Memorandum Pad, of which the following is a specification, reference being had to the accompanying drawing, forming part thereof.

Fig. I is a front elevational view of a combination calendar memorandum pad showing my new design.

Fig. II is a side elevational view of the same.

I claim:

The ornamental design for a combination calendar memorandum pad, as shown.

CHARLES F. BROWN,
